UNITED STATES PATENT OFFICE

108,018

DESIGN FOR A TOILET TANK TOP

Charles C. Norris, Riverside, Calif.

Application November 10, 1937, Serial No. 72,744

Term of patent 7 years

To all whom it may concern:

Be it known that I, Charles C. Norris, a citizen of the United States, residing at Riverside, in the county of Riverside and State of California, have invented a new, original, and ornamental Design for a Toilet Tank Top, of which the following is a specification, reference being had to the accompanying drawing, forming part thereof.

In the drawing,

Fig. 1 is a perspective view of a toilet tank top embodying my new design.

Fig. 2 is a top plan of the toilet tank top of Fig. 1.

Fig. 3 is an end view thereof.

I claim:

The ornamental design for a toilet tank top, as shown.

CHARLES C. NORRIS.
